UNITED STATES PATENT OFFICE.

RUSSELL L. LONG, OF MORGANTOWN, WEST VIRGINIA.

HAT-PIN GUARD.

1,156,300.

Specification of Letters Patent. Patented Oct. 12, 1915.

Application filed January 16, 1915. Serial No. 2,660.

To all whom it may concern:

Be it known that I, RUSSELL L. LONG, a citizen of the United States, residing at Morgantown, in the county of Monongalia and State of West Virginia, have invented certain new and useful Improvements in Hat-Pin Guards; of which the following is a specification, reference being had to the accompanying drawings.

10 My invention relates to hat pin guards, and the object of the invention is the provision of a very easily made and entirely effective device of this character which will hold securely upon the pointed extremity 15 of the hat pin and yet may be readily removed therefrom.

My invention is illustrated in the accompanying drawings, wherein—

20 Figure 1 is a side elevation of a guide of the character described, partly broken away to show the internal construction; Fig. 2 is a longitudinal section of a hat pin guard shown in Fig. 1; Fig. 3 is a longitudinal section in a plane at right angles to Fig. 2; 25 Fig. 4 is a transverse section enlarged on the line 4—4 of Fig. 2; Fig. 5 is a face view of the entrance end of the guard.

Referring to these figures, 2 designates a metallic shell, which may be made integral 30 or in sections, and which is preferably slightly tapering in form, though not necessarily so. This shell at its outer end is formed with a head 3. At the entrance end of the shell there is disposed a reentrant cone 4 of metal. This cone extends inward to a point 5 and then is prolonged in the form of two oppositely disposed resilient fingers 6. These fingers are transversely concave on their confronting faces, as illustrated clearly in Fig. 4. The fingers gradually approach each other toward the inner end of the shell 2 and then are outwardly turned as at 7. These fingers are somewhat resilient.

45 Disposed within the case 2 is an annular filling 8, of some material which will have a certain degree of softness or resilience. This filling may be of wax, rubber or some other composition, and as clearly illustrated 50 in Fig. 4, the fingers 6 will protect this filling from wear and abrasion upon the insertion of the pin.

As illustrated in Figs. 2 and 3, the hat pin 9 is passed through the hat and the pro-

55 tector or guard is disposed upon the pin point. The guard will be guided into position on the tapering point of the pin by the reentrant cone 4. Then as the guard is shifted on the pin the point of the pin will 60 enter between the fingers 6. These will 65 grip the pin point, the wax, rubber or other filling acting to support these fingers, while the fingers will protect the wax backing and prevent its being worn. If wax or rubber alone were used in the interior of the shell, 70 in a short time the entrance of the pin point into the guard would tend to wear or tear the inner surface of the wax or rubber and the guard would very shortly become loose. By providing the concave fingers 75 70 I prevent this and at the same time secure frictional contact of the filling with the pin at the points 8a in Fig. 4. The frictional engagement of the filling with the pin and frictional engagement of the pin with the 75 fingers is such as to prevent any accidental disengagement of the guard from the pin, permitting, however, the relatively easy removal of the guard whenever desired.

While I have illustrated a particular form. 80 for the guard, it is to be understood of course that other forms might be used having a more ornamental value without departing from the spirit of the invention.

Having described my invention, what I 85 claim is:

A hat pin guard comprising a metallic shell having a reentrantly conical portion at its entrance end, a pair of longitudinally tapering oppositely disposed fingers extending from the inner end of the conical portion, disposed in approximately parallel relation but converging toward the inner end of the shell, said fingers being transversely concave and spaced from each other, and 95 an annular filling of yielding material disposed within the shell, filling the space between said fingers and the shell and the space between the lateral edges of said fingers whereby the filling will come into frictional engagement with the pin.

100 In testimony whereof I hereunto affix my signature in the presence of two witnesses.

RUSSELL L. LONG.
